US00D633595S

(12) **United States Design Patent**
Reid et al.

(10) **Patent No.:** **US D633,595 S**
(45) **Date of Patent:** **** Mar. 1, 2011**

(54) **FILTER BLOCK FOR LIQUID FILTRATION**

4,753,728 A 6/1988 Vander Bilt et al.
4,859,386 A 8/1989 Vanderbilt et al.

(75) Inventors: **Roger P. Reid**, Caldwell, ID (US);
Bruce D Saaski, Nampa, ID (US)

(73) Assignee: **Omnipure Filter Company, Inc.**,
Caldwell, ID (US)

DESCRIPTION

U.S. PATENT DOCUMENTS

532,939 A	1/1895	Balch
2,580,209 A	12/1951	Wiley
2,720,278 A	10/1955	Wiley
3,375,933 A	4/1968	Rodman
3,538,020 A	11/1970	Heskett et al.
3,721,072 A	3/1973	Clapham
3,746,642 A	7/1973	Bergstrom
3,788,486 A	1/1974	Bergstrom
4,306,971 A	12/1981	Hankammer
4,664,683 A	5/1987	Degen et al.
4,665,050 A	5/1987	Degen et al.
4,666,600 A	5/1987	Hankammer

FIG. 1 is a front perspective view of the invented design for a filter block for liquid filtration.

FIG. 2 is a front view of the filter block of FIG. 1.

FIG. 3 is a rear view of the filter block of FIG. 1.

FIG. 4 is a right side view of the filter block of FIG. 1, with the left side view being a mirror image.

FIG. 5 is a top view of the filter block of FIG. 1; and,

FIG. 6 is a bottom view of the filter block of FIG. 1.
